UNITED STATES PATENT OFFICE.

ERNST H. HUENEFELD, OF CINCINNATI, OHIO.

DESIGN FOR A HEATING-STOVE.

SPECIFICATION forming part of Design No. 31,015, dated June 13, 1899.

Application filed May 15, 1899. Serial No. 716,960. Term of patent 14 years.

To all whom it may concern:

Be it known that I, ERNST H. HUENEFELD, of Cincinnati, in the county of Hamilton and State of Ohio, have invented a new and original Design for Heating-Stoves, of which the following is a full, clear, and exact description, reference being had to the accompanying drawing, forming a part thereof.

The accompanying drawing is a view in perspective from the front of the stove.

The leading feature of my design consists of a stove-body oval in horizontal cross-section, mounted on legs, the upper ends of which latter overlap the lower edge of the oval body.

A represents the oval stove-body, provided near its upper and lower edges with corrugations or beads *a*. The body is mounted upon the legs *C*, the upper ends of which overlap the lower edge of the body. Projecting above the top is the circular collar *d*, and surmounting the collar is the conical part *e*.

What I claim is—

The design for a heating-stove as herein shown and described.

ERNST H. HUENEFELD.

In presence of—

J. R. CARTER,
JACOB P. BAUER, Jr.
